UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

MINING APPARATUS

Application filed October 9, 1926. Serial No. 140,578.

This invention relates to mining apparatus and more particularly to mining machines of the so called shear or vertical cutter type adapted to operate from the mine trackway.

An object of this invention is to provide an improved mining machine of the wheel mounted type wherein the mining machine is adapted to insert a shear or vertical cut in the coal face while mounted on the mine trackway. Still another object of this invention is to provide an improved shearing machine having a pivoted cutter bar and improved and simplified mechanism for swinging the cutter bar about its pivot. A still further object of this invention is to provide an improved mining machine having improved mechanism associated with the bar swinging mechanism for driving the wheels of the truck. These and other objects of my invention will, however, hereinafter more fully appear. In the accompanying drawings I have shown for purposes of illustration one form which my invention may assume in practice.

In these drawings,—

Fig. 1 is a side elevation of the improved mining apparatus, the cutter bar and machine body being shown in a plurality of positions as indicated by dotted lines.

Fig. 2 is a plan view of the apparatus shown in Fig. 1.

Fig. 3 is a transverse horizontal sectional view taken on line 3—3 of Fig. 1, parts being shown in elevation.

Fig. 4 is a vertical transverse sectional view taken on line 4—4 of Fig. 3.

Fig. 5 is a central longitudinally extending horizontal sectional view taken on line 5—5 of Fig. 1 and illustrating the plural speed transmission gearing.

Fig. 6 is a developed sectional view taken on line 6—6 of Fig. 1 and illustrating the bar pivot and a portion of the bar swinging mechanism and cutter chain driving mechanism.

In this illustrative embodiment of my invention I have shown a truck frame 1 mounted on wheels 2 adapted to move relative to a mine trackway 3 in the usual manner. The truck frame 1 specifically comprises longitudinally extending parallel angle members 4

held in rigid spaced relation by means of transverse plates 5. The angle members 4 carry in a suitable manner the running gear for the truck wheels 2. As shown, a generally rectangular elongated machine frame or body 7 is slidable longitudinally relative to the truck frame 1 and is guided thereon by means of parallel interlocking guiding members 8 and 9 rigidly secured to the opposite sides of the machine frame and truck frame respectively, the members 9 being secured to the truck frame 1 by means of angle members 10 as clearly shown in Fig. 6. The machine frame 7 is supported by and slides directly on the transverse plates 5, the latter being rigidly secured to the angle members 4 at various longitudinally spaced points. However, it is obvious that rollers or other anti-friction devices may be provided between the machine 6 and the truck frame. Further, the machine frame 7 is provided with an elongated plane cutter bar 11 movable in a vertical plane and about the outer edges of which an endless cutter bit carrying cutter chain 12 is adapted to be circulated, the cutter chain moving in a fixed orbit. The cutter chain is adapted to be driven by means of a usual drive sprocket 13 as clearly shown in Fig. 6. The cutter chain drive sprocket 13 is disposed at the front end of the machine frame 7 and is rotatable about a horizontal axis extending transversely of the machine frame. As shown, the elongated cutter bar 11 is pivoted, as at 14, on an axis coincident with the axis of the cutter chain sprocket 13 and has secured integral therewith cylindrical bearing members 15 disposed at opposite sides of the sprocket, the members 15 respectively engaging bearing surfaces 16 and 16'. The sprocket 13 is adapted to be driven from the driving motor, the horizontal longitudinally extending armature shaft of which is clearly shown in Fig. 5 as at 17, through transmission gearing clearly described in a pending application of one Morris P. Holmes, Ser. No. 619,839, filed Feb. 19, 1923. As the specific driving connections between the motor and the cutter chain drive sprocket do not enter into this invention, further detailed description of the same is deemed unnecessary.

necessary other than to state that the sprocket 13 may be either connected or disconnected from the motor at will.

In specifically describing the improved mechanism for swinging the cutter bar 11 about its pivot 14 it will herein be observed that the rear end of the armature shaft 17 of the driving motor (see Fig. 5) has suitably secured thereto a spur pinion 18 which is adapted to drive the truck wheel driving mechanism, and the improved mechanism for swinging the cutter bar about its pivot, to be hereinafter described, including plural speed transmission gearing and controlling clutches substantially similar to those described in the pending application Ser. No. 619,839 mentioned above at a slow speed in one direction or at a fast speed in an opposite direction without reversing the motor. In specifically describing the fast speed transmission mechanism it will be noted that the pinion 18 meshes with a spur gear 19 suitably journaled within bearings 20 carried by the machine frame. The gear 19 has secured thereto and rotatable therewith a spur pinion 21 which meshes with a larger internal gear 22. The hub 23 of the gear 22 is herein also journaled on a suitable bearing sleeve 24 on a sleeve clutch member 25 keyed as at 26 to a longitudinally disposed horizontal main driving or transmission shaft 27 journaled at its opposite ends in suitable bearings 28 and 29 carried within the machine frame. Moreover, it will be noted that the member 25 carries a series of friction clutch discs 30 which are interleaved with a corresponding series of clutch discs 31 carried by the sleeve of the internal gear. As shown, the sleeve on the internal gear is also provided with a plurality of radially located longitudinally extending slots 32 receiving radial fingers 33 formed on an interlocking member 34 keyed to the hub of a pinion 35 freely rotatable on the shaft 27. Interposed between these fingers 33 are friction clutch operating fingers 36 carried by a cylindrical plane clutch operating member 37 disposed coaxially with the hub of the member 34. These fingers 36 extend longitudinally into contact with the adjacent end disc of the clutch 30, 31. As shown, the rear end of the shaft 27 has secured thereto as by a key 38, a spur pinion 39 which meshes with a spur gear 40 journaled within suitable bearings carried by the machine frame. The spur gear 40 has secured thereto and rotatable therewith a spur pinion 41 which meshes with a larger internal gear 42 keyed as at 43, to a longitudinally extending horizontal shaft 44 disposed coaxially with the transmission shaft 27. The shaft 44 is journaled within spaced alined roller bearings 45 and 46 suitably carried by the machine frame. It will thus be noted that rotation of the armature shaft 17 will be transmitted to the

pinion 18, gear 19, pinion 21, internal gear 22, friction clutch discs 30, 31, clutch member 25, shaft 27, pinion 39, gear 40, pinion 41, internal gear 42 and the shaft 44 to rotate the latter at a predetermined high or fast speed whenever the clutch controlling member 37 is operated to connect the clutch 30, 31. It will here further be noted that this speed may be lowered at will by slipping the friction discs 30, 31 of the clutch.

Now referring specifically to the slow speed transmission it will be noted that when the clutch operating member 37 is in inoperative position and the clutch 30, 31 is released, power will still be transmitted through the interlocking member 34 to the pinion 35 which is freely rotatable on the shaft 27. This pinion 35 in turn meshes with a gear 47 disposed coaxially with the gear 21 and this gear has secured thereto and rotatable therewith a pinion 48 which meshes with a spur gear 49 disposed coaxially with and rotatable on the shaft 27. This gear 49 has secured thereto and rotatable therewith a spur pinion 50 which meshes with a spur gear 51 arranged coaxially with the gear 47 and this gear has secured thereto and rotatable therewith a spur pinion 52. The spur pinion 52 meshes with an internal gear 53 substantially similar to the internal gear 22. The internal gear 53 also houses a friction clutch substantially similar to the clutch heretofore described in connection with the clutch discs 30, 31 and this clutch includes series of interleaved clutch discs 54 and 55 certain of which are carried on a clutch member 56 keyed as at 57 to the shaft 27 while others are carried by a sleeve formed on the internal gear 53. A clutch retaining member 58 is provided keyed as at 59 to the hub of the spur pinion 39 and this clutch member in this instance has no interlocking function and is only a disc retaining member. An axially movable cylindrical plane clutch operating member 60 surrounds the hub of the clutch member 58 and is provided with longitudinally extending fingers 61 which are adapted to engage the adjacent end disc of the clutch discs 54, 55. The clutch operating members 37 and 60 may be operated to alternatively apply their respective clutches by means of suitable shifter mechanism which is clearly described in the pending application mentioned above and including an operating handle 62 conveniently located at the rear end of the machine (see Figs. 1 and 2). As a result of this mechanism above described, although the clutch 30, 31 is disconnected, rotation will constantly be imparted through the pinion 35, gear 47, pinion 48, gear 49, pinion 50, gear 51, pinion 52, internal gear 53, clutch discs 54, 55, clutch member 56, pinion 39, gear 40, pinion 41, internal gear 42 to the shaft 44 so that when the clutch 54, 55 is connected

the shaft 44 will be rotated at a slow speed in an opposite or reverse direction from the fast speed previously described. Here it will also be evident that by slipping the friction discs 54, 55 of the slow speed clutch this speed may be rediced at will.

As clearly shown in Fig. 3 the shaft 44 is made hollow and has telescopically arranged therein a shaft 65, the shaft 65 being held in non-rotative relation relative to the shaft 44 by means of a spline connection 66. It will be evident that the shaft 44 may be moved longitudinally relative to the shaft 65 while the driving relation therebetween is constantly maintained. The rear end of the shaft 65 is journaled on ball bearings 67 suitably carried within a housing or casing 68 rigidly secured in a suitable manner to the angle members 4 of the truck frame 1. The shaft 65 has secured thereto at the rear end thereof as by a key 69 a bevel pinion 70 which constantly meshes with larger bevel gears 71 and 72 rotatably mounted on bearing sleeves 73 and 74 respectively surrounding and supported by a horizontal shaft 75 disposed transversely of the truck frame and journaled at its opposite ends in ball bearings 76 suitably carried by the housing 68. The bevel gears 71, 72 rotate in opposite directions and constitute a reversing mechanism for the shaft 75. Carried upon each of the bevel gears 71 and 72 is a series of clutch discs 77 which is interleaved with a corresponding series of clutch discs 78 carried by each of the clutch housing members 79 keyed as at 80 to the shaft 75. Interposed between the gears 71, 72 and encircling the hubs thereof are axially movable clutch applying members 81 and 82 each having fingers projecting within the gears into engagement with the adjacent end disc of the series of clutch discs 77 and 78. As shown, a roller equipped shipper yoke 83 is provided, the rollers of which engage the adjacent plane surfaces of the clutch applying members 81, 82 and this shipper yoke is keyed to a vertically disposed shaft 84 suitably rotatably mounted within the housing 68. The shaft 84 has secured thereto at its upper end an operating lever 85 (see Figs. 1 and 2). It will thus be evident that when the operator suitably swings the lever 85 about its pivot the shipper yoke is consequently swung and the desired clutch 77, 78 is applied there-by connecting one or the other of the bevel gears 71, 72 in operative driving relation with the shaft 75, rotating the latter selectively in opposite directions. The shaft 75 may also be rotated at either a fast or at a slow speed under control of the clutches 30, 31 and 54, 55 described above under the control of the operating member 62.

In this instance, journaled on the shaft 75 and connectible thereto is a worm 86. The mechanism for connecting the worm 86 to the

shaft 75 will be later described. The worm 86 meshes with a worm gear 87 (see Fig. 4) keyed as at 88 to a horizontal shaft 89 disposed below the shaft 75 and extending longitudinally of the machine at one side thereof.

The forward end of the shaft 89 is threaded as at 90, and is threadedly connected, as at 91, to a suitable nut member 92 secured as by screws 93 to the side of the machine frame 7 at the rear end thereof. As shown in Figs. 1 and 6 the cutter bar 11 has secured thereto as by rivets 94 an angle member 95, the latter in turn being secured as by bolts 96 to a member 97. The member 97 is rotatably mounted, as at 98, on a bearing sleeve 99 encircling and supported by a cylindrical bearing portion 100 preferably formed integral with the machine frame 7 and disposed coaxially with the axis of bar swing. As illustrated, the member 97 has preferably formed integral therewith a depending arm 101 having formed therein an elongated slot 102 extending radially of the bar pivot. Mounted in the slot 102 is a block 103 pivotally supported, as at 104, on a horizontal pin 105 disposed transversely of the machine and threadedly connected, as at 106, within a block 107 rigidly secured to one of the angle members 4 of the truck frame. From the foregoing description it will be evident that when the shaft 65 is connected in driving relation with the motor and when the shaft 75 is connected to one of the bevel gears 71, 72 the screw 90 may be rotated thereby effecting axial movement of the nut 92 relative to the screw and consequently moving the mining machine 6 in its guides longitudinally relative to the truck frame. As the machine frame 7 moves longitudinally relative to the truck frame the relatively stationary block 103 acts as a fulcrum or abutment for the arm 101 and consequently the cutter bar, to which the arm 101 is rigidly secured, is swung about its pivot 14, the elongated slot 102 permitting swinging movement of the arm 101 relative to the block 103 on the truck frame. By connecting the shaft 75 to the one or the other of the bevel gears 71 and 72 and suitably controlling the clutches 30, 31 and 54, 55 the screw 90 may be rotated in either direction and at either a fast or a slow speed in either direction and consequently the cutter bar may be swung about its pivot as desired.

In specifically describing the improved means for driving the truck wheels from the motor carried by the machine frame 7 it will be observed that secured to the end of the shaft 75 opposite from the worm 86 as by a key 109 is a spur gear 110. Arranged coaxially with the gear 110 is a spur gear 111 preferably formed integral with a shaft 112 disposed coaxially with the shaft 75 and journaled in spaced alined ball bearings 113 suitably carried by the housing 68. The gear 111

is connectible in driving relation with the gear 110 by means of an axially movable internal shipper gear 114. As clearly shown in Fig. 3 the shaft 112 has secured thereto at its outer end a chain sprocket 115 which is connected by means of an endless drive chain 116 to a sprocket 117 suitably rigidly secured to the rear truck axle. As shown, in Figs. 1 and 2 the front and rear truck axles are connected together by means of a chain and sprocket connection 117^a. Again referring to Fig. 3 it will be observed that the worm 86 has preferably formed integral therewith at the outer end thereof a spur gear 118 which is connectible by means of an axially movable internal shipper gear 119 to a spur gear 120 keyed, as at 121, to the shaft 75. The mechanism for alternatively connecting the gears 111 and 118 in driving relation with shaft 75 will now be described. Cooperating with the peripheral grooves in the internal shipper gears 114 and 119 respectively are shipper yokes 122 and 123 secured as by pins 124 at the opposite ends of an actuating rod or shaft 125 slidably mounted within bores 126 formed within lateral lugs 127, the latter being formed integral with the housing 68. As shown, longitudinally spaced stop pins 128 are carried by the rod 125 and are adapted to alternatively engage the adjacent inner sides of the lugs 127, thereby preventing excessive movement of the shipper gears in either direction. The rod 125 is vertically slotted intermediate its ends as at 129 and cooperating with this slot is a shipper lever 130 pivoted on the housing 68. It will thus be evident that when the lever 130 is grasped by the operator and swung about its pivot to effect axial movement of the rod 125 in one direction, the gears 110, 111 are connected by the shipper gear 114 while the gears 118, 120 are disconnected by the shipper gear 119. When the shipper rod 125 is shifted axially in the opposite direction the gears 110, 111 are released and the gears 118, 120 are connected. It is obvious that the gears 111 and 118 may only be alternatively driven.

Suitably secured to the rear truck axle is a frictional braking device 135 (see Fig. 2) and this braking device is adapted to be operated through suitable connections 136 and 137, the rear end of the latter connection being connected to an operating lever 138. This frictional braking device is adapted to control rotation of the truck wheels when the mining apparatus is moving over an inclined trackway and is also adapted to lock the truck wheels against rotation during the cutting operation.

In the operation of my improved mining apparatus, it will be noted that when the latter is moving rapidly about the mine the clutch 77, 78 is applied connecting the bevel gear 71 in driving relation with the shaft

75 and the truck drive gears 110, 111 are connected by the clutch shipper gear 114, it being understood that the motor is running and the fast speed clutch 30, 31 is applied and consequently the shaft 65 is revolving at a high speed. When it is desired to drive the mining apparatus rearwardly relative to the trackway at a high speed the bevel gear 71 is released from the shaft 75 and the bevel gear 72 is connected to the shaft 75 by means of its controlling clutch 77, 78. When the machine is disposed adjacent the working face the operator disconnects the bevel gear 71 from the shaft 75 and shifts the rod 125 axially, disconnecting the truck drive gears 110, 111 and connecting the bar swing gears 118, 120 in driving relation with the shaft 75 by means of the shipper gear 119. The clutch 77, 78 is then applied, connecting the bevel gear 71 to the shaft 75, it being understood that the shaft 65 is still rotating at a high speed, and the screw 90 is rotated at a fast speed and the machine frame 7 is moved rearwardly longitudinally relative to the truck frame, the reaction of the arm 101 against the relatively stationary block 103 carried by the truck frame effecting fast swinging movement of the cutter bar from the full line position shown in Fig. 1 upwardly about its pivot to the upper dotted line position in that figure, thereafter the bevel gear 71 being released from the shaft 75 and rotation of the screw 90 is of course discontinued. The operator then suitably connects the cutter chain drive sprocket 13 to the motor and the cutter chain 12 is rapidly circulated about the outer edges of the cutter bar 11 in a usual manner. The rod 125 is then shifted axially, disconnecting the bar swing gears 118, 120 and connecting the truck drive gears 110, 111. The fast speed clutch 30, 31 is then released and the slow speed clutch 54, 55 is applied and the shaft 65 is consequently rotated in an opposite direction at a slow speed. The clutch 77, 78 is then applied, connecting the bevel gear 72 to the shaft 75 and the cutter bar is then dumped into the coal, the apparatus moving bodily along the trackway at that time. After the dumping cut is completed the bevel gear 72 and the truck drive gear 111 are disconnected from the shaft 75 and the bevel gear 71 and the bar swing gear 118 connected to the shaft 75 and the screw 90 is rotated at a slow speed in the opposite direction, consequently moving the machine frame 7 forwardly relative to the truck frame and swinging the cutter bar at a slow or cutting speed downwardly from its upper dotted line position to its lower dotted line position shown in Fig. 1. During this swinging cut the truck wheels are held against rotation by means of the frictional braking device 135. After the swinging cut is completed, the braking device 135 is released, the bevel gear 71 is dis-

connected from the shaft 75, and the rod 125 is again slid axially, disconnecting the bar swing gears 118, 120 and again connecting the truck drive gears 110, 111. The bevel gear 71 is then again connected to the shaft 75 and the cutter bar is then retracted from the face at a cutting speed, the apparatus moving bodily rearwardly along the trackway at that time. After the withdrawal cut 5 is completed the cutter chain is disconnected from the motor, the bevel gear 71 is disconnected from the shaft 75, and the operator then shifts the rod 125 axially, disconnecting the truck drive gears 110, 111 and connecting 10 the bar swing gears 118, 120. The slow speed clutch 54, 55 is then released and the fast speed clutch 30, 31 is again applied and the shaft 65 is consequently rotated at a high speed. The bevel gear 71 is then connected 15 to the shaft 75 and the screw 90 is then rotated at a high speed moving the machine frame rearwardly relative to the truck frame and the bar is consequently swung upwardly about its pivot at a fast speed to the full line 20 position shown in Fig. 1. The bar swing gears 118, 120 are then disconnected and the truck drive gears 110, 111 are again connected, the gear 71 disconnected and the gear 72 connected to shaft 75, and the apparatus 25 is driven bodily rearwardly from the face along the mine trackway at a high speed. These and other operations and advantages of my improved mining apparatus will be clearly apparent to those skilled in this art.

30 While I have in this application specifically illustrated and described one form which my invention may assume in practice, it will be understood that this form of the same is shown for purposes of illustration 35 and that the invention may be modified and embodied in various other forms without departing from its spirit or the scope of the appended claims.

What I claim as new and desire to secure 40 by Letters Patent is:

1. In a mining apparatus, a wheeled truck frame, a machine body slidably guided on said frame and having mounted thereon a pivoted cutter bar carrying an orbitally movable cutter chain, and means including a pivotal connection between said cutter bar and said truck frame and lying wholly outside of said cutter chain orbit for swinging said bar about its pivot including mechanism for moving 45 the machine body longitudinally relative to said truck frame to effect bar swing.

2. In a mining apparatus, a wheeled truck frame, a machine body slidably guided on said frame and having mounted thereon a 50 pivoted cutter bar carrying an orbitally movable cutter chain, and means for swinging said bar about its pivot including mechanism for moving the machine body longitudinally relative to said truck frame to effect bar swing 55 and including connections between said cut-

ter bar and said truck frame and disposed wholly outside of said cutter chain orbit.

3. In a mining apparatus, a wheeled truck frame, a machine body slidably guided thereon and having mounted thereon a pivoted cutter bar, and means for swinging said cutter bar about its pivot including mechanism carried by said machine body and truck, and including a telescopic driving connection whereby the machine body may be moved longitudinally relative to the truck frame to effect bar swing while the driving relation therebetween is maintained. 70

4. In a mining apparatus, a wheeled truck frame, a machine body slidably guided thereon and having mounted thereon a pivoted cutter bar carrying an orbitally movable cutter chain, and means including a pivotal connection between said cutter bar and said truck and lying wholly outside the cutter chain orbit for swinging said cutter bar about its pivot and mechanism for moving said machine body longitudinally relative to said truck frame in either direction to effect swinging movement of said cutter bar to positions wherein the cutting portion of said bar lies at opposite sides of a longitudinal plane including said cutter bar pivot. 80

5. In a mining apparatus, a wheeled truck frame, a machine body slidably guided thereon and having mounted thereon a pivoted cutter bar carrying an orbitally movable cutter chain and a driving motor in said body, and means driven by said motor including a pivotal connection between said bar and truck frame and lying wholly outside of said cutter chain orbit for swinging said cutter bar about its pivot including mechanism for moving said machine body relative to said truck frame to effect bar swing. 95

6. In a mining apparatus, a wheeled truck frame, a machine body slidably guided thereon and having mounted thereon a pivoted cutter bar carrying an orbitally movable cutter chain, a driving motor in said body, and means driven by said motor including a pivotal connection between said cutter bar and said truck and lying wholly outside of said cutter chain orbit for swinging said cutter bar about its pivot and mechanism for moving said machine body relative to said truck frame in either direction to effect swinging movement of said cutter bar to positions wherein the cutting portion of said bar lies at opposite sides of a longitudinal plane including said cutter bar pivot. 110

7. In a mining apparatus, a wheeled truck frame having guides thereon extending longitudinally thereof, a machine body supported on said truck frame and having guides thereon cooperating with said guides, said machine body having mounted thereon a pivoted cutter bar carrying an orbitally movable cutter chain, and means including a pivotal 115 connection between said cutter bar and truck frame. 120

- connection between said bar and said truck frame and lying wholly outside of said cutter chain orbit for swinging said cutter bar about its pivot including mechanism for moving 5 said machine body in said guides longitudinally of said truck frame to effect bar swing. 8. In a mining apparatus, a wheeled truck frame having guides thereon extending longitudinally thereof, a machine body supported 10 on said truck frame and having guides thereon cooperating with said guides, said machine body having mounted thereon a pivoted cutter bar carrying an orbitally movable cutter chain, and means for swinging said 15 cutter bar about its pivot including mechanism for moving said machine body in said guides longitudinally of said truck frame to effect bar swing, and connections between said cutter bar and said truck frame and lying 20 wholly outside of said cutter chain orbit. 9. In a mining apparatus, a wheeled truck frame, a machine body slidably supported thereon and movable longitudinally relative thereto, said machine body having mounted 25 thereon a pivoted cutter bar carrying an orbitally movable cutter chain, and means for swinging said cutter bar about its pivot including mechanism for moving said machine body longitudinally relative to said truck 30 frame, and connections between said cutter bar and said truck frame and lying wholly outside of said cutter chain orbit. 10. In a mining apparatus, a wheeled truck frame, a machine body supported thereon and 35 movable longitudinally relative thereto, said machine body having mounted thereon a pivoted cutter bar, and means for swinging said cutter bar about its pivot including mechanism for moving said machine body longitudinally relative to said truck frame, and connections between said cutter bar and said truck frame including a slotted arm secured to said bar and a pivot block carried 40 by said truck and cooperating with the slot in said arm. 11. In a mining apparatus, a wheeled truck frame, a machine body slidably supported thereon and movable longitudinally relative thereto, said machine body having mounted 45 thereon a pivoted cutter bar carrying an orbitally movable cutter chain and a driving motor in said body, and means driven by said motor for swinging said cutter bar about its pivot including mechanism for moving said machine body longitudinally relative to said truck frame, and connections between said cutter bar and said truck frame and lying wholly outside the orbit of said cutter chain. 12. In a mining apparatus, a wheeled truck frame, a machine body slidably mounted thereon and movable longitudinally relative thereto, said machine body having mounted thereon a pivoted cutter bar carrying an orbitally movable cutter chain, and means for 55 60 65 70 75 80 85 90 95 100 105 110 115 120 125 130
- swinging said cutter bar about its pivot to positions wherein the cutting portion thereof lies at opposite sides of a longitudinal plane including the cutter bar pivot and including connections between said cutter bar and said truck frame and lying wholly outside of said cutter chain orbit. 13. In a mining apparatus, a wheeled truck frame, a machine body mounted thereon and movable longitudinally relative thereto, said machine body having mounted thereon a pivoted cutter bar, and means for swinging said cutter bar about its pivot including connections between said cutter bar and said truck frame, said connections including a radial arm secured to said cutter bar and disposed angularly relative thereto, and an abutment on said truck frame slidably engaging said arm. 14. In a mining apparatus, a wheeled truck frame, a machine body slidably guided thereon and having mounted thereon a pivoted cutter bar swingable in a vertical plane and a driving motor in said body, and means driven by said motor including a reversing mechanism carried by said truck frame and relative to which said body is movable for swinging said cutter bar about its pivot in opposite directions and mechanism for moving said machine body longitudinally relative to said truck frame to effect swinging movement of said cutter bar to positions wherein the cutting portion thereof lies at opposite sides of a horizontal plane including the cutter bar pivot. 15. In a mining apparatus, a wheeled truck frame, a machine body slidably guided thereon and having mounted thereon a pivoted cutter bar carrying an orbitally movable cutter chain and a driving motor in said body, and means driven by said motor for swinging said cutter bar about its pivot in opposite directions including mechanism for moving said machine body longitudinally relative to said truck frame to effect swinging movement of said cutter bar to positions above and below a horizontal plane including the cutter bar pivot, and connections between said cutter bar and said truck frame and lying wholly outside of said cutter chain orbit. 16. In a mining apparatus, a wheeled truck frame, a machine body slidably guided thereon and having mounted thereon a pivoted cutter bar carrying an orbitally movable cutter chain, a connection between said cutter bar and said truck and lying wholly outside of said cutter chain orbit, and means for swinging said cutter bar about its pivot in opposite directions at different speeds including mechanism for moving said machine body longitudinally relative to said truck frame in either direction to effect bar swing. 17. In a mining apparatus, a wheeled truck frame, a machine body supported thereon and

- movable longitudinally rectilinearly relative thereto, said machine body having mounted thereon a pivoted cutter bar carrying an orbitally movable cutter chain, a connection between said cutter bar and said truck and lying wholly outside of said cutter chain orbit, and means for swinging said cutter bar about its pivot in opposite directions at different speeds including mechanism for moving said machine body relative to said truck frame in either direction to effect bar swing. 5
18. In a mining apparatus, a wheeled truck frame, a machine body slidably guided thereon, said machine body having mounted thereon a pivoted cutter bar carrying an orbitally movable cutter chain, a connection between said cutter bar and said truck and lying wholly outside of said cutter chain orbit, and motor driven fast and slow speed transmission mechanism in said body, and means for swinging said cutter bar about its pivot including mechanism driven by said transmission mechanism for moving said machine body longitudinally relative to said truck frame to effect bar swing. 10
19. In a mining apparatus, a wheeled truck frame having guideways, a machine body thereon slidably guided in said guideways, said machine body having mounted thereon a pivoted cutter bar carrying an orbitally movable cutter chain, a connection between said cutter bar and said truck and lying wholly outside of said cutter chain orbit, and motor driven fast and slow speed transmission mechanism in said body, and means for swinging said bar about its pivot including mechanism driven by said transmission mechanism for moving said machine body longitudinally in said guideways relative to said truck frame to effect swinging movement of said cutter bar to positions at opposite sides of a longitudinal plane including said cutter bar pivot. 15
20. In a mining apparatus, a wheeled truck frame having guideways, a machine body thereon slidably guided in said guideways, said machine body having mounted thereon a pivoted cutter bar carrying an orbitally movable cutter chain and motor driven fast and slow speed transmission mechanism in said body, and means for swinging said bar about its pivot including mechanism driven by said transmission mechanism for moving said machine body longitudinally in said guideways relative to said truck frame to effect swinging movement of said cutter bar to positions at opposite sides of a longitudinal plane including said cutter bar pivot. 20
21. In a mining apparatus, a wheeled truck frame having guideways thereon, a machine body supported on said truck frame and slidably guided in said guideways, said machine body having mounted thereon a pivoted cutter bar carrying an orbitally movable cutter chain, a connection between said cutter bar and said truck and lying wholly outside of said cutter chain orbit, and means for swinging said cutter bar about its pivot including mechanism for moving said machine body in said guideways relative to said truck frame at different speeds to effect swinging movement of said cutter bar to positions at opposite sides of a longitudinal plane including said cutter bar pivot. 25
22. In a mining apparatus, a wheeled truck frame having guideways thereon, a machine body supported on said truck frame and slidably guided in said guideways, said machine body having mounted thereon a pivoted cutter bar carrying an orbitally movable cutter chain, a connection between said cutter bar and said truck and lying wholly outside of said cutter chain orbit, and means for swinging said cutter bar about its pivot including mechanism for moving said machine body in said guideways relative to said truck frame at different speeds in opposite directions to effect swinging movement of said cutter bar in opposite directions to positions at opposite sides of a longitudinal plane including said cutter bar pivot. 30
23. In a mining apparatus, a wheeled truck frame having guideways thereon, a machine body slidably guided in said guideways, said machine body having mounted thereon a pivoted cutter bar and a motor in said body, means for swinging said cutter bar about its pivot including mechanism for moving said machine body in said guideways longitudinally relative to said truck frame to effect bar swing, and mechanism driven by said motor for driving the wheels of said truck to propel the apparatus bodily along the mine trackway at a cutting speed to effect sumping and withdrawal movements of said cutter bar. 35
24. In a mining apparatus, a wheeled truck frame having guideways thereon, a machine body slidably guided in said guideways, said machine body having mounted thereon a pivoted cutter bar and a motor in said body, means for swinging said cutter bar about its pivot including mechanism for moving said machine body in said guideways longitudinally relative to said truck frame to effect bar swing, and mechanism driven by said motor for driving the wheels of said truck at different speeds to propel the apparatus bodily along the mine trackway, said wheel driving mechanism including means for driving the truck wheels at a cutting speed to effect sumping and withdrawal movements of said cutter bar. 40
25. In a mining apparatus, a wheeled truck frame having guideways thereon, a machine body slidably guided in said guideways, said machine body having mounted thereon a piv- 45

oted cutter bar and a motor in said body, means for swinging said cutter bar about its pivot including mechanism for moving said machine body in said guideways longitudinally relative to said truck frame, and mechanism driven by said motor for driving the wheels of said truck in opposite directions to propel the apparatus bodily along the mine trackway in opposite directions at a cutting speed to effect sumping and withdrawal movements of said cutter bar.

26. In a mining apparatus, a wheeled truck frame having guideways thereon, a machine body slidably guided in said guideways and having mounted thereon a pivoted cutter bar, means for swinging said cutter bar about its pivot including mechanism for moving said machine body in said guideways longitudinally relative to said truck frame, and means for driving the wheels of said truck, said bar swinging means and said truck wheel driving means being only alternatively operable.

27. In a mining apparatus, a wheeled truck frame, a machine body slidably supported thereon and movable longitudinally relative thereto, said machine body having mounted thereon a pivoted cutter bar, means for swinging said cutter bar about its pivot, and means for driving the wheels of said truck, said bar swinging means and said truck driving means being only alternatively operable.

28. In a mining apparatus, a wheeled truck frame, a machine body slidably supported thereon and movable longitudinally relative thereto, said machine body having mounted thereon a pivoted cutter bar and a driving motor, means driven by said motor for swinging said cutter bar about its pivot including mechanism for moving said machine body longitudinally relative to said truck frame, and means driven by said motor for driving the wheels of said truck, said bar swinging means and said truck driving means being only alternatively connectible to said motor.

29. In a mining apparatus, a wheeled truck frame, a machine body supported thereon and movable longitudinally relative thereto, said machine body having mounted thereon a pivoted cutter bar, and means for swinging said cutter bar about its pivot including mechanism for moving said machine body relative to said truck frame and a pivoted connection between said bar and said frame at a point in advance of the front truck axle.

30. In a mining apparatus, a wheeled truck frame having guideways thereon, a machine body slidably guided in said guideways and having mounted thereon a pivoted cutter bar, mechanism for moving said machine body in said guideways longitudinally relative to said truck frame to effect swinging movement of said cutter bar, and means for driving the wheels of said truck, said bar swinging means and said truck wheel driving means being only alternatively operable.

31. In a mining apparatus, a wheeled truck frame, a machine body slidably supported thereon and movable longitudinally relative thereto, said machine body having mounted thereon a pivoted cutter bar and a driving motor in said body, means driven by said motor for moving said machine body longitudinally relative to said truck frame to effect swinging of said cutter bar about its pivot, and means driven by said motor for driving the wheels of said truck, said bar swinging means and said truck driving means being only alternatively connectible to said motor.

32. In a mining apparatus, a wheeled truck frame, a machine body supported thereon and movable longitudinally relative thereto, said machine body having mounted thereon a pivoted cutter bar, and means for moving said machine body relative to said truck frame to effect swinging of said cutter bar about its pivot including a pivoted connection between said bar and said frame at a point in advance of the front truck axle and located a substantial distance below the pivotal axis of said cutter bar.

33. In a mining apparatus, a wheeled truck frame, a machine body supported thereon and movable longitudinally relative thereto, said machine body having mounted thereon a pivoted cutter bar swingable in a vertical plane, and means for moving said machine body relative to said truck frame to effect swinging movement of said cutter bar upwardly and downwardly to positions wherein the cutting portion of said bar lies above and below a horizontal plane including said cutter bar pivot and including a pivoted connection between said bar and said frame at a point in advance of the front truck axle and located a substantial distance below the pivotal axis of said cutter bar.

34. In a mining apparatus, a portable base frame, a sliding frame mounted thereon, cutting mechanism including a swingable cutter bar carrying an orbitally movable cutter chain and pivotally mounted on said sliding frame, a pivotal connection between said cutter bar and said base frame and lying wholly outside of the orbit of said cutter chain, and means for moving said sliding frame relative to said base frame for swinging said cutter bar about its pivot to effect a swinging cut.

35. In a mining apparatus, a portable base frame, a sliding frame mounted thereon, cutting mechanism including a swingable cutter bar carrying an orbitally movable cutter chain, a pivotal connection between said cutter bar and said base frame and lying wholly outside the orbit of said cutter chain, a connection between said cutter bar and said sliding frame, and means for moving said sliding frame relative to said base frame to swing said bar relative to said base frame to effect a swinging cut.

36. In a mining apparatus, a portable base frame, a sliding frame mounted thereon, cutting mechanism including a swingable cutter bar carrying an orbitally movable cutter chain, said sliding frame being pivotally connected to said cutter bar about an axis lying within the orbit of said cutter chain, a pivotal connection between said cutter bar and said base frame and lying wholly outside the orbit of said cutter chain, and means for moving said sliding frame relative to said base frame to swing said bar relative to said base frame to effect a swinging cut. 70
37. In a mining apparatus, a portable base frame, a sliding frame thereon carrying a motor, cutting mechanism including a swingable cutter bar carrying an orbitally movable cutter chain, a pivotal connection between said cutter bar and said base frame and lying wholly outside the orbit of said chain, and mechanism driven by said motor for moving said sliding frame relative to said base frame to swing said cutter bar about its pivot to effect a swinging cut. 75
38. In a mining apparatus, a portable base frame, a sliding frame thereon, cutting mechanism including a swingable cutter bar carrying an orbitally movable cutter chain and pivotally connected to said base frame about an axis lying wholly outside the orbit of said cutter chain, a connection between said sliding frame and said cutter bar, and means for moving said sliding frame relative to said base frame to swing said bar relative to said frames to effect a swinging cut. 80
39. In a mining apparatus, a portable base frame, a sliding frame thereon carrying a motor, cutting mechanism including a swingable cutter bar carrying an orbitally movable cutter chain and pivotally connected to said base frame about an axis lying wholly outside the orbit of said cutter chain, a connection between said sliding frame and said cutter bar, and means driven by said motor for moving said sliding frame relative to said base frame to swing said bar relative to said frames to effect a swinging cut. 85
40. In a mining apparatus, a portable base frame, cutting mechanism thereon including a swingable cutter bar carrying an orbitally movable cutter chain and pivotally connected to said base frame about an axis lying wholly outside the orbit of said cutter chain, and means including a frame slidably mounted on said base frame and pivotally connected to said cutter bar for swinging the latter relative to said base frame to effect a swinging cut. 90
41. In a mining apparatus, a portable base frame, a machine frame mounted thereon and movable relative thereto, cutting mechanism including a swingable cutter bar carrying an orbitally movable cutter chain and pivotally mounted on said machine frame, an angularly disposed arm secured to said cutter bar and
